ATTORNEYS.

UNITED STATES PATENT OFFICE.

JOHN A. ROBERTSON AND CHARLES F. SPEIDEL, OF ROCHESTER, NEW YORK,
ASSIGNORS TO EASTMAN KODAK COMPANY, OF ROCHESTER, NEW YORK,
A CORPORATION OF NEW YORK.

DESIGN FOR A CAMERA CASING.

Application filed February 16, 1922. Serial No. 723. Term of patent 14 years.

To all whom it may concern:

Be it known that we, JOHN A. ROBERTSON and CHARLES F. SPEIDEL, citizens of the United States, residing at Rochester, in the county of Monroe and State of New York, have invented a new, original, and ornamental Design for Camera Casings, of which the following is a specification, reference being had to the accompanying drawing, forming a part thereof.

Fig. 1 is a perspective view of a camera casing showing our new design;

Fig. 2 is a plan view of the back of the camera casing shown in Fig. 1;

Fig. 3 is an end elevation of the camera casing shown in Fig. 1.

One feature of our design is the camera case covering contrasting with the outlining bands. The camera case is preferably covered with a dark material such as black leather and the outlining bands are of the color of the metal of which the camera case is made, such as aluminum. The silver colored metal bands thus form a contrasting outline for the panels of leather.

We claim:

The ornamental design for a camera casing, as shown and described.

Signed at Rochester, New York, this 14th day of February, 1922.

JOHN A. ROBERTSON.
CHARLES F. SPEIDEL.
